UNITED STATES PATENT OFFICE

WALTER L. DANIEL, OF LUBBOCK, TEXAS

PHOTOGRAPH HOLDER

Application filed September 19, 1929. Serial No. 393,770.

This invention relates to a photograph holder, one of the objects being to provide a device that can be used as a paper weight, table ornament or the like and also serve as a container for a strip of photographs having means for holding the strip normally retracted and rolled.

Another object is to provide a device of this character the external appearance of which corresponds with the object or objects portrayed on one of the photographs contained in the housing whereby the external appearance of the housing will promptly identify the particular structure illustrated by the pictures contained therein.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of the device. Figure 2 is a plan view thereof.

Figure 3 is a central vertical section.

Figure 4 is a bottom plan view, the bottom or cover strip being removed.

Figure 5 is an enlarged section on line 5—5, Figure 4.

Figure 6 is a section on line 6—6, Figure 3, showing the picture strip partly withdrawn to expose an illustration corresponding with the external appearance of the housing.

Figure 7 is a section on line 7—7, Figure 3.

Referring to the figures by characters of reference, 1 designates a housing formed of papier-mâché, plaster of Paris, or any other suitable plastic material molded, cast, pressed or otherwise formed to portray a structure of interest to the user. In the present instance the housing 1 has been shaped to portray the approach or entrance portion of a cave. It is to be understood, however, that the body portion can be molded to represent a building

or other structure having numerous points of interest therein.

In the back portion of the bottom of the body 1 is formed a relatively deep rectangular recess 2 from which extends a guide channel 3 having parallel sides and opening through the bottom of the front portion of the body 1. The top of the recess 2 merges along curved lines into the top of the channel 3 and the top faces of the recess and channel can be reinforced by a wear strip 4 of tough paper or other suitable material glued or otherwise connected to the adjacent surfaces of the body. This wear strip is not necessary if metal or other wear resisting material be used for the body.

The recess 2 is formed with shallow extensions 5 at the ends thereof adapted to receive the end portions of a plate 6 which extends throughout the length of recess 2 and has its bottom surface flush with the bottom surface of the body 1. This plate is formed with upstanding ears 7 and seated in these ears are the trunnions 8 of a spring-actuated roller 9 of the type used with window shades although much smaller. One of the trunnions 8 is square or rectangular in form to prevent rotation of the shaft upon which the roller turns, as is customary in devices of this character. This roller has a strip 10 fastened at one end thereto and normally wound thereon and the free end of strip 10 has a reinforcing cross-strip 11 fastened thereto and adapted normally to fit snugly in the outer end portion of the channel 3. This strip 11 is held against movement back into the channel 3 by the end of the wear strip 4 as shown particularly in Figure 3. A small tab 12 is attached to the reinforcing strip 11 and constantly projects forwardly from the bottom portion of the body 1 where it can be easily grasped.

The spring in the roller 9 serves to hold the strip 11 pressed against the end of the wear strip 4 with the strip 10 normally wound about the roller in the illustrated form of the invention. The reinforcing strip 11 is shaped upon its outer edge to conform to the shape of the exterior of the body, where the channel or slot opens

through it, whereby it constitutes a closure for the open end of the channel or slot in its normal retracted position. If no wear strip is provided the channel may be so shaped as to provide an abutment or abutments for the reinforcing strip to seat against to position it in proper relation to the open end of the slot to completely close the same when in its normal retracted position.

10 For the purpose of retaining the plate 6 in the body and holding the strip 10 in its channel 3, a cover strip 13 is attached to the bottom of the body 1 so as to provide a finish therefor and also a smooth surface for contact with the structure on which the device is supported.

As before explained, the body 1 is adapted to be shaped to represent some object of interest. If, as shown in the drawings, it is 20 shaped to represent a cave, the strip 10 can be provided with a series of pictures, indicated at 14, illustrating not only the entrance to the cave as portrayed by the body but also points of interest inside of the cave or adjacent thereto. The prospective customer will be attracted by the external appearance of the structure which represents the object of interest and by pulling on the tab 12 the strip 10 can be unwound from the roller 9 so 30 that the pictures relating to the structure illustrated or portrayed by the body will be successively brought to view. After all of these pictures have been examined the strip 10 can be released so that the spring in the 35 roller 9 will return the strip to its housed position as illustrated in Figures 2 and 3.

While the body 1 portrays an object of interest and is used primarily for housing a strip of pictures, the recess 15 enables it to 40 be used as an ash tray or the like. Furthermore a pair of the articles can be used as book ends. If desired, the recess in the body can be so formed as to hold ink. With certain modification, the body might be used for 45 purposes other than those mentioned.

What is claimed is:

1. An article of manufacture comprising a base and a representation of an object of interest carried thereby, a recess in said base 50 shaped to receive a roller and having a narrow slot extending to the exterior, a spring roller mounted in said recess, a flexible strip wound on said roller having one end secured thereto and its free end extending through 55 said slot, and a stiffening element on said free end normally housed in said slot to close its open end.

2. The combination with a structure having a recess in the bottom thereof and a shallow channel leading from said recess to the front of the bottom portion of said structure, of a spring roller mounted for rotation in the recess, a flexible strip normally wound on the roller and guided in the channel, a reinforcing 65 strip at the free end of said flexible strip nor-

mally housed in the outer end portion of the channel and limited in its movement in one direction thereby, and a cover strip secured to the bottom of said structure and extending across the recess and channel to conceal the 70 same and provide a bottom finish for the structure.

3. The combination with a structure having a recess in the bottom thereof and a shallow channel leading from said recess to the 75 front of the bottom portion of said structure, of a wear strip mounted on the top walls of the recess and channel and terminating inwardly from the outer end of the channel, a spring roller mounted for rotation in the 80 recess, a flexible strip normally wound on the roller and guided in the channel, a reinforcing strip at the free end of said flexible strip normally housed in the outer end portion of the channel and limited in its movement in 85 one direction by the end of the wear strip, and a cover strip secured to the bottom of said structure and extending across the recess and channel to conceal the same and provide a bottom finish for the structure.

4. An article of manufacture comprising a base and a representation of an object of interest carried thereby, a recess in said base shaped to receive a picture strip coil and having a narrow slot extending to the exterior, a coiling means mounted in said recess, a flexible strip carried by said coiling means having one end secured thereto and its free end extending through said slot, and a stiffening element on said free end normally housed in said slot to close its open end.

In testimony that I claim the foregoing as my own, I have hereto affixed my signature.

WALTER L. DANIEL.
